PAVEMENT FINISHING MACHINE

Albert H. Hinkle and Alvin C. Rasmussen, Indianapolis, Ind., assignors to Insley Manufacturing Company, Indianapolis, Ind., a corporation

Application February 29, 1932, Serial No. 595,914

17 Claims. (Cl. 94—48)

In the surfacing of roads, it is obviously desirable to provide a smooth riding surface as expeditiously as possible.

The present invention relates to a machine which will actuate upon the surface of a roadway to level the same and for levelling either material laid upon a new subgrade, or material applied on the top of an existing road for resurfacing or refinishing operations.

More particularly the present invention provides a machine which will simultaneously tamp and level the surface and in such a manner that the surface of the road will be formed in the proper slope; and in which the tamping and the levelling actions may be performed selectively either together or independently.

A still further object of the invention resides in the provision of the tamping instrumentalities disposed longitudinally of the surface upon which they are to act. The importance of this will be apparent when it is recalled that longitudinal finishing of the highway surfaces obviates the formation of transverse ridges or ripples in the roadway after completion of the finishing operations, these ridges being frequently of considerable degree of objectionableness because of the jarring effect produced upon vehicles traveling along such transversely ridged roadways.

The present invention therefore provides a machine which will longitudinally tamp the surface of the road materials so that the surface will be leveled and finished in conformity with the requirements of a longitudinally finished highway surface, this longitudinal finishing being found to prevent the formation of the above mentioned transverse ridges, thereby providing a better riding surface.

A further feature of the machine of this invention lies in the provision of instrumentalities whereby, through an oscillating action, a smooth surface will be obtained, all irregularities being smoothed to give an even surface, this being obtained through the use of tamping beams of considerable length arranged upon actuating mechanism so that alternate beams will be raised while the remaining beams will be in contact with the surfacing material being operated upon.

A still further feature of the invention lies in the provision of suitable traction devices for the machine, which is thereby rendered self-propelable along the roadway, and which is adapted to move along either the surfacing material or on the subgrade itself, or along the usual road forms.

These and further objects and advantages will be made clear from a consideration of the de-

tailed description which will be hereinafter given, and the detailed construction and operation of the machine will also become clear therefrom, and from the accompanying drawings, in which

Figure 1 is a side elevation of the machine of the present construction, certain details being omitted for clarity.

Figure 2 is a plan view of the machine, parts being broken away.

Figure 3 is an end view of the machine, showing details of the tamping devices.

Referring more particularly to the drawings, it will be seen that the machine comprises a lower, or main frame, A, and an upper, or auxiliary, frame B. This main frame A carries the tracks 1 at the forward and rear of the frame, along which run the wheels 2, which carry the upper frame B, upon which are mounted various operating instrumentalities, as will be clear hereinafter.

Upon the frame B there is carried the source of power C from which power is suitably taken off, as through the sprocket wheel 3, which drives, through a chain 4, the sprocket wheel 5 of such size as to effect desirable reduction in speed, and which actuates the shaft 16, one end of which operates in the bearing 7 and which has keyed to it a clutch member 8, which is adapted to selectively engage the clutch member 6 for controlling the actuation of a pulley 9, over which passes a transmission belt, or other suitable power transmitting device 10. The drive 10 is passed over a pulley 11 carried by the crank shaft 12, which operates in suitable bearings 13 and 13a. One end of the crank shaft 12 carries the crank arms 14, while on the other end there is mounted the crank arm 15. The purpose of these arms will be later described.

The pulley 9 is carried by the shaft 16, as before described, there being provided also a bearing 17, the end of the shaft terminating in a worm drive 18 of standard construction for actuating the sleeve shaft 19 which is carried by the through shaft 20 extending from crank arm 13 to crank arm 28a.

The sleeve shaft 19 carries the clutch 22 for engagement with the beveled gear 21, the clutch being also engageable with the opposing beveled gear 23, both beveled gears 21 and 23 running loose on shaft 19 except when either is engaged by clutch 22, a third beveled gear 24 being driven by gear 21 or 23 as the clutch 22 is actuated, for transmission of power to the traction devices for propelling the machine either forwardly or rear- 55

wardly along the roadway. The clutch and gear system is of standard construction and the transmission of power to the traction devices will be brought out in more detail hereinafter. The 5 sleeve shaft 19, through a clutch 25, actuates the through-shaft 20 operating in the bearings 27 and 27a, and carrying the crank arms 28 and 28a to which are secured the rods 29 and 29a respectively.

10 One end of the rod 29 is secured to the frame A at 30, and as the crank arm 28 rotates through a complete circle the rod 29 causes the upper frame B to oscillate relatively to the frame A through the wheels 2 operating on the tracks 1 of the 15 frame A.

In a similar manner the rod 29a, attached at its outer end at 30a, to the lower frame A, as described just above in connection with rod 29, provides the upper frame B with oscillating instrumentalities at each end. Clutch 25 will be understood to be operable from the operator's position on the platform 60, by a suitable lever, in the usual well understood manner.

20 Referring back to the crankshaft 12, it will be seen that the crank arm 14 carries the oscillating connecting rod 31, which is connected with the rocker arm 32 for rocking the shaft 33, this shaft carrying adjacent each end the oppositely directed rocker arm unit 34, having the oppositely extending arms 35 and 36 positioned to rock vertically, the arms being suitably offset as clearly shown. Only one unit of these arms is illustrated, it being understood that the construction actuated thereby will be duplicated at the end 35 of the shaft 33 which is not shown.

25 Through the end of each arm which is formed into a bushing, is passed a screw rod 37 and 38 of suitable length for the hereinafter described purpose. Through suitable nuts and washers 40 which will be clearly seen, there are positioned on each rod the upper and lower buffer springs 39 and 40, the lower springs exerting an additional pressure on the tamping beams at the end of the stroke and allowing for unevenness of roadway.

30 Each rod 37 and 38 carries also a cross beam, which is conveniently formed of suitably spaced steel channel members 41, each beam engaging an intermediate block 42 and 43, held in place by the tamping beams 44 and 45 respectively, these 35 tamping beams being of substantial length and being aligned so that alternate beams 44 will be secured to the blocks 43, the remaining beams 45 being secured to the blocks 42, it being understood that the channel members 41 extend across

40 the width of the assembled tamping beams. The blocks and beams are conveniently of wood or any other suitable material of suitable dimensions and are held together by washers and nuts 46 and 47 on the ends of the respective screw rods or 45 other practical means, the entire assembly being secured on the rods through the provision of washers 48 and nuts 49. It will therefore be apparent that as the shaft 33 rocks, alternate tamping bars will be raised and lowered to tamp the 50 surface of the pavement while at the same time being reciprocated laterally by the oscillations of the frame B. The control of this tamping mechanism is effected through suitable actuation of the clutch 6, 8 which controls the actuation of the 55 power transmitting drive 10, as previously described.

50 It will be seen that the tamping mechanism just described is duplicated at the other end of the machine, the actuating rod 31a being the counter- 75 part of the actuating rod 31, being mounted on

the crank 15 for oscillation in a manner entirely similar to that described in connection with the rod 31. The rod 31a is suitably fastened to the rocker arm 32a under actuation of the shaft 33a which in turn carries the rocker arm unit 34a having the vertically moving rocker arms 35a and 36a which are counterparts of the corresponding arms 35 and 36, previously described.

5 The rocker arm units 34 and 34a rock on their respective shafts in unison toward and away from each other. The connecting arms 31 and 31a being thereby simultaneously in tension when the rocker arms are drawn inwardly toward each other and in compression when the rocker arms are pushed outwardly away from each other. 10 During the time that these rocker arms are pulled inwardly toward each other, the outer cross beams carried by rods 38 are lifted so that half of the tamping beams are raised. Simultaneously the two inner cross beams carried by rods 37 are depressed and the alternate tamping beams are forced downwardly and perform their tamping action at the end of the stroke. These rods 31 and 31a pulling the rocker arms simultaneously 15 towards each other or away from each other so as to balance the inertia effect of one against the other, reducing vibration.

20 It has been already said that these tamping beams are of considerable length to assure spanning of all the low spots, and will pound on the high spots until these are brought down to a common, uniform level.

25 Passing now to the consideration of power transmission from the source of power C to the traction devices herein referred to generally as D and illustrated in the form of rollers, although endless traction belts or wheels may be substituted therefor, if desired, it will be remembered that it has already been described that such power is transmitted from the clutch 22 being brought 30 into engagement with the bevel gears 21 or 23, as desired, to effect driving of the said gears through the rotation of the sleeve shaft 19 and source of power, the rotation of the bevel gear 21 or 23 being transmitted to the intermediate bevel gear 35 40 24, the driving of which actuates the sprocket wheel 51 over which passes a sprocket chain 52 to a sprocket wheel 53, thereby driving the shaft 54. Upon the shaft 54 is mounted a sleeve 55a, carrying a sprocket wheel or equivalent power transmitting instrumentality 55, which by means of the sprocket chain or belt 56, correspondingly 45 actuates the sprocket 57 on the rear axle 58 carrying the drive wheels 59, to thereby propel the machine along the roadway. The actuation 50 of sprocket 55 is controlled through the clutch 56a.

55 The direction of travel is of course determined by the engagement of the gear 24 with either the gear 21 or the gear 23.

60 The various clutch instrumentalities mentioned herein are of generally standard construction and are operated through various control devices such as levers and the like, and which are not shown, forming no part of this invention, and which are in ready access to an operator riding on the platform 60.

65 Instrumentalities are also provided for adjusting the depth of the tamping action, such instrumentalities being positioned at the front and rear axles of the machine and which are indicated in general at 61 and 62, the front axle being indicated at 58a. These instrumentalities adjust the height of the frame A above the level surface through the actuation of the hand screw

63 and 64 operating on the front and rear axles of the machine respectively. Adjustment of these members correspondingly adjusts the depth of stroke of the tamping beams to thereby facilitate the leveling action of these beams.

It will be observed from the construction that through the actuation of the clutch instrumentalities 25 and 56a, the oscillatory motion of the frame B and the tamping beams may be controlled independently of the travel of the machine along the roadway, this latter being, as has already been described, performed through the actuation of the gear 24 taking power from the shaft 19. It will therefore be seen that the machine is adapted for leveling action independently of travel along the road, and also independently of the tamping. If clutch 6, 8 be disengaged so as to stop the tamping action, and the washers and nuts 48 and 49, and 48a and 49a, be removed and the upper buffer springs around each of the rods 37, 38, 37a, and 38a be removed, all the tamping beams will be dropped into contact with the pavement, and by then actuating the clutches 25 and 25a so as to start the oscillation of the frame B, it will be seen that the tampers will be moved laterally across the surface of the pavement, which is troweled or smoothed off laterally in the same fashion that a plasterer uses a float for leveling off the surface of freshly applied plaster. In addition to this, the machine can be traveled back and forth in the longitudinal direction of the road, and by so timing the longitudinal movement of the machine, a circular troweling of the surface can be performed. This circular troweling of the surface performed as a finishing operation, will greatly assist in the obtaining of a perfect level surface. Obviously, this circular troweling of the road surface is not desired when block pavements are being operated upon.

It may be noted in passing that the connecting rods 31 and 31a with the arms 32 and 32a may be made adjustable as clearly shown in Figure 1 so as to assure the desired amount of oscillation of the shafts irrespective of the position of the machine away from the surface of the pavement. This adjustment is indicated by the apertures 65 and 65a in the arms 32 and 32a respectively.

It will be observed that the tamping beams 44 and 45 are of a length many times their width, and it will be seen that the amount of oscillation of the frame B will be an amount at least equal to the space between the successive tamping beams. This assures a continuously level surface, finished longitudinally and transversely.

It will be understood that a machine constructed in accordance with the herein described principles is advantageously usable not only for leveling earth roadways, tar-macadam roadways, concrete or other surfacing materials of a plastic nature, but is well adapted for levelling brick or any kind of block pavement, operating to pound down high bricks or blocks to a common level; and where plastic materials are used as paving materials, the tamping action of the beams will be to fill in depressions in the subgrade with a material which will be tamped as effectively as will the paving material which lies over the high spots, thus assuring a pavement of equal density throughout.

Having thus described our invention, what we claim as new and desire to secure by Letters Patent of the United States, is

1. A road finishing machine comprising a portable frame to be advanced longitudinally of a

road subgrade over pavement material to be finished, tamping devices disposed longitudinally of the machine and lengthwise of the road subgrade over which the machine travels, the tamping devices being of a length many times the width thereof, operating means for said tamping devices, and means for imparting up and down and sidewise movement to said tamping devices to cause the same to deliver a blow to the road, together with power means to move the frame longitudinally of the road whilst the tamping devices are moved up and down and sidewise.

2. In a road tamping machine, in combination, a portable frame to be advanced lengthwise of the road, tamping devices disposed longitudinally on said frame, mechanism for imparting up and down and lateral oscillation of the tamping devices relatively to the road aggregates for engagement with the latter on the down stroke and to smooth the latter while in such engagement.

3. A road finishing machine comprising a portable frame to be advanced longitudinally of a road subgrade over pavement material to be finished, tamping devices disposed longitudinally of the machine and lengthwise of the road subgrade over which the machine travels, operating means for said tamping devices, and mechanism for causing up and down and sidewise movement of the tamping devices for certain engaging action on the road materials of a subgrade, and instrumentalities whereby the tamping devices may be caused to operate upon the road materials without said up and down movement primarily for smoothing or troweling the materials.

4. In a road finishing machine, in combination, a portable frame to be advanced lengthwise of the road subgrade, a series of spaced tamping devices carried by the frame and located longitudinally thereof, and therefore also lengthwise of the road, and mechanism carried by the frame for imparting up and down and sidewise movement to the said tamping devices, said up and down movement being effective to deliver a blow to the surface with which the tamping devices engage the sidewise movement being at least co-extensive with the spaces separating the tamping devices.

5. In a road finishing machine, in combination, a portable frame to be advanced lengthwise of a subgrade carrying road aggregates or pavement materials, a series of longitudinal tampers carried by said machine adapted to deliver a blow to the road and constructed of a length many times the width thereof, mechanism supporting these tampers from the frame and for operating them up and down and sidewise, together with mechanism for propelling the frame while the tampers are being operated.

6. A paving machine, comprising, in combination, a frame, a second frame carried by the first frame and adapted to move transversely thereof, tamping devices carried by the machine, a source of power, and actuating mechanism driven from the source of power for actuating the said tamping devices, the said mechanism comprising a crank shaft, connecting rods carried by the crank shaft, a second shaft interconnected with the connecting rod and adapted to be oscillated thereby as the said crank shaft rotates, and instrumentalities carried by the oscillatable shaft for imparting rapid reciprocatory movement to the tamping devices in a vertical direction.

7. A paving machine, comprising, in combination, a frame, a second frame carried by the first

- frame and adapted to move transversely thereof, tamping devices carried by the machine, a source of power, and actuating mechanism driven from the source of power for actuating the said tamping devices, the said mechanism comprising a crank shaft, connecting rods carried by the crank shaft, a second shaft interconnected with the connecting rod and adapted to be oscillated thereby as the said crank shaft rotates, and instrumentalities carried by the oscillatable shaft for imparting vertical movement to the tamping devices to cause the same to deliver a blow to the road, the last named instrumentalities including rocker arms mounted on the oscillatable shaft for rocking in a vertical direction, a rod passing through each rocker arm, a beam carried on each rod and extending transversely of the machine, the said tamping devices being secured by the rod to each of the transversely extending beams in selected groups, whereby a paving surface will be operated on by each group of tamping devices alternately for leveling the said surface, for the full longitudinal length of the tamping beams and for full longitudinal length of the tampers.
25. 8. A paving machine of the character described, comprising, in combination, a portable frame, a second frame carried by the portable frame and movably mounted thereon, a source of power in the second frame, driving connections between the first frame and source of power to oscillate the second frame relatively to the first frame, tamping and leveling devices carried by the machine, and driving instrumentalities for selectively actuating the tamping devices, whereby the said tamping devices may be actuated vertically for delivering blows to a road surface and for sweeping action.
30. 9. A paving machine of the character described, comprising in combination, a frame, a second frame carried by the portable frame and movably mounted thereon, a source of power on the second frame, driving connections between the first frame and source of power to oscillate the second frame transversely of the first frame, a plurality of comparatively long laterally spaced tamping devices carried by the machine, and instrumentalities for vertically actuating the tamping devices for causing them to operate upon a paving surface while oscillating the devices with the second frame to thereby level out high spots in a paving surface.
35. 10. A paving machine of the character described, comprising, in combination, a portable frame, tracks mounted on the frame and extending transversely thereof, a second frame having wheels running in the said tracks on the first frame, a source of power carried by the second frame, driving connections between the first frame and source of power for oscillating the second frame relatively to the first frame, tamping devices carried by the machine, driving mechanism for vertically actuating the tamping devices to cause them to deliver a levelling force to a paving surface while oscillating the device through the oscillations of the second frame to thereby level out high spots in a paving surface, and instrumentalities for interrupting the vertical actuation of the devices while continuing oscillation thereof for laterally smoothing the paving.
40. 11. A paving machine of the character described, comprising, in combination, a frame, a second frame carried by the first frame and laterally movable relatively thereto, driving means for producing transverse oscillating movement of
- the second frame, tamping devices carried by the second frame adapted to tamp a road, and operating instrumentalities for lifting selected units of the devices while lowering the remainder thereof for completely covering a surface of paving being operated upon for leveling out all high spots in the said paving.
45. 12. A paving machine of the character described, comprising, in combination, a frame, a second frame carried by the first frame and laterally movable relatively thereto, driving means for producing transverse oscillatory movement of the second frame, tamping devices carried by the second frame, and operating instrumentalities for alternately lifting and lowering selected units of the devices during the said oscillatory movement thereof for completely covering a surface of paving being operated upon for leveling out all high spots in the paving, the operating instrumentalities comprising an oscillatable shaft, lifting arms mounted on the shaft, demountable, resiliently mounted carrying rods actuated by the lifting arms, a beam extending transversely across the machine and operating with each of the carrying rods, means on the carrying rods for interconnecting selected units of the aforesaid tamping devices with each of the beams and arms, and actuating instrumentalities connecting the oscillatable shaft with the source of power for oscillating the shaft.
50. 13. A paving machine of the character described, comprising, in combination, a frame, a second frame carried by the first frame and laterally movable relatively thereto, driving means for producing transverse oscillatory movement of the second frame, tamping devices carried by the second frame, and operating instrumentalities for alternately lifting and lowering selected units of the tamping devices during the said oscillatory movement thereof for completely covering a surface of paving being operated upon for leveling out all high spots in the paving during oscillation of the frame, and means for independently interrupting the tamping and oscillating actions respectively while continuing the other of the said actions.
55. 14. A paving machine of the character described, comprising, in combination, a lower frame adapted to travel along a roadway, an upper frame reciprocably carried on the lower frame, mechanism for reciprocating the upper frame relatively to the lower frame, pavement tamping members carried by the machine and adapted to act upon a pavement surface to tamp out high spots therein for leveling the surface, instrumentalities for vertically operating the tamping members while oscillating them with the frame, and means for controlling the oscillating action without affecting the action of the tamping instrumentalities.
60. 15. A paving machine of the character described, comprising, in combination, a lower frame adapted to travel along a roadway, an upper frame reciprocably carried on the lower frame, mechanism for reciprocating the upper frame relatively to the lower frame, pavement tamping members carried by the machine and adapted to act upon a pavement surface to tamp out high spots therein for leveling the surface, instrumentalities for vertically operating the tamping members while oscillating them with the frame, and means for controlling the action of the tamping instrumentalities without affecting the oscillating action.
65. 16. A paving machine of the character de-

scribed, comprising a pair of relatively reciprocal frame elements, tamping beams carried thereby and extending longitudinally beneath the machine for continuously acting upon a pavement surface longitudinally thereof to tamp out irregularities therein, a source of power, and driving mechanism interconnecting the source of power with the tamping beams to vertically actuate the bars and effect the engagement thereof with the pavement surface.

17. A paving machine of the character described, comprising a pair of relatively reciproca-

ble frame elements, tamping beams carried thereby and extending beneath the machine for continuously acting upon a pavement surface to tamp out irregularities therein, a source of power, driving mechanism interconnecting the source of power with the tamping beams to vertically actuate the beams upon the pavement surface, and instrumentalities at each end of the machine for maintaining the bars continuously level during tamping operations.
